2,458,473

DETONATOR

James D. Jordan, Washington, D. C., assignor to
the United States of America as represented by
the Secretary of the Navy

Application January 26, 1943, Serial No. 473,650

2 Claims. (Cl. 102—71)

1

This invention relates to detonators for explosive projectiles and has particular reference to a novel detonator having two independently operable detonating means included in a unitary construction.

One object of the invention resides in the provision of a novel detonator for projectiles which includes both mechanically and electrically operable detonating means mounted in a single body. The body is preferably of cylindrical shape, whereby it may be readily mounted in the usual cylindrical casing of the projectile, and is formed with a chamber for receiving an electrically operable squib. The body is also provided with a bore communicating with the chamber, and a recess in the front end of the body communicates with the bore. A detonating charge is disposed in the bore, and the recess contains a mechanically actuated explosive device, such as a fulminate cap, for firing the charge in the bore. The squib is adapted to be fired electrically through a detonating circuit which may be closed automatically by a radio apparatus in the projectile in response to proximity of a target. The body of the detonator is preferably mounted in the projectile to the rear of a clockwork mechanism, as shown in the above identified application, so that the mechanically actuated explosive device is in line with a firing pin operable by the clockwork mechanism. With this construction, if the radio apparatus or other automatic means should fail to fire the squib electrically, the explosive device is actuated by the firing pin to set off the detonating charge and thereby explode the projectile. Thus, the detonator of my invention includes both a main detonating element and an independently operable auxiliary detonating element which serves as a safety device to insure explosion of the projectile in its flight.

Another object of the invention is to provide a detonator of simple and compact construction which may be fired either electrically or, in the event of failure of the electrical means, by a mechanically operable element.

These and other objects of the invention may be better understood by reference to the accompanying drawing, in which

Fig. 1 is a longitudinal sectional view of part of a projectile embodying one form of the new detonator;

Fig. 2 is an enlarged transverse sectional view of the detonator shown in Fig. 1, and

Figs. 3, 4 and 5 are sectional views on the lines 3—3, 4—4 and 5—5, respectively, in Fig. 2.

In the drawing, the numeral 10 designates an

2

explosive projectile comprising a casing 11 and a nose 12 threaded in the front end of the casing. The explosive charge (not shown) in the casing is adapted to be detonated electrically upon closing of a normally open switch 13 which may be actuated automatically by a radio apparatus (not shown) in response to proximity of the projectile to a target, as disclosed in the above-identified application of M. A. Tuve et al. The switch 13, as shown, is connected in series with a battery 14 and the detonator 15 of my invention through wires 16 and 17. A clockwork mechanism 18 is mounted in the projectile casing in front of the detonator and is adapted to operate a firing pin 18a at a predetermined time interval after the projectile is fired, the clockwork mechanism having suitable adjusting means for varying the time interval.

The detonator 15 comprises a cylindrical body 20 having a generally circular opening 21 extending through its central portion. A web 22 projects into the opening from one side of the body and abuts against an electrically operable squib 23 extending across the opening at right angles to the web. The squib 23 is seated at its ends in suitable recesses in the body and is provided with terminals 24 and 24a.

A detonating charge 26 is disposed in a central bore in the web 22, the bore being inclined rearwardly toward the squib 23 and communicating at its inner end with the opening 21. At its outer end, the bore opens into a recess 27 in the front end of the body 20. A mechanically operable explosive device, such as a fulminate cap 28, is seated in the bore 27 in line with the firing pin 18a of the clockwork mechanism. The body 20 may be provided on its opposite faces with cover plates 30 and 31, the rear plate 31 having an explosion discharge opening 32 and an opening 33 through which the wires 16 and 17 extend into the squib chamber 21. From the chamber 21, the wires extend through suitable routes 33 in the body to the squib terminals 24 and 24a.

In operation, when the switch 13 is closed, the squib 23 is energized electrically through the circuit including battery 14, with the result that the detonator explodes through opening 32 in the rear cover plate and fires the usual booster (not shown) to the rear of the detonator. In the event that the squib 23 should fail to operate for any reason, such as failure of the radio means for closing the switch 13, the clockwork mechanism 18 operates the firing pin 18a after a predetermined time interval, whereupon the fulminate cap 28 is fired and sets off the detonating charge

26. The latter then explodes through the inner end of its bore into the chamber 21 and through the rear cover plate 31 to the booster.

It will be apparent that the detonator of my invention occupies a relatively small space and may be readily mounted in the projectile casing. The housing 20 contains two independently operable detonating means which are so disposed that neither one interferes with the operation of the other. The web 22 serves not only to house the auxiliary detonating charge 26 but also to lend lateral support to the electrically operable squib in the chamber 21.

I claim:

1. In a detonator, a body having an opening, an electrically operable squib extending across the opening and seated at its ends in the body, a web extending transversely from one side of the body into the opening and abutting at its free end against the squib, the web having a bore perpendicular to and communicating at one end with the opening and at the other end with a recess in the body, a detonating charge in the bore, and a mechanically operable explosive device in the recess for firing said charge. 15

2. In a detonator, a body having an opening, an electrically operable squib extending across the opening and seated at its ends in the body, a web extending transversely from one side of the body into the opening and abutting at its free end against the squib to support the squib, the web having a bore inclined inwardly from the front face of the body to the rear face thereof, the bore being perpendicular to and communicating at its rear end with said opening and at its front end with a recess in the body, a detonating charge in the bore, and a mechanically operable explosive device in the recess for firing said charge. 5
